FIG. 1

FIG. 4

FIG. 3

INVENTOR:

WILLIAM C. GRAVES

By Miller Chindell Parker
ATTY'S.

UNITED STATES PATENT OFFICE.

WILLIAM C. GRAVES, OF CHICAGO, ILLINOIS.

LOCK.

Application filed December 24, 1921. Serial No. 524,569.

To all whom it may concern:

Be it known that I, WILLIAM C. GRAVES, a citizen of the United States, residing at Chicago, in the county of Cook and State 5 of Illinois, have invented certain new and useful Improvements in Locks, of which the following is a specification.

This invention relates to improvements in locks and consists generally in the provision of a lock having the well-known advantages of the "Yale" lock and which embodies a novel simplified arrangement and construction of parts which can be manufactured economically.

More specifically, the invention provides an improved arrangement which is especially adapted to be embodied in a lock similar to the flat cabinet type for use on mail boxes or the like, and which cannot be opened by using an exploring pick as is frequently the case with these smaller locks.

Other objects, advantages and uses of the invention will appear in the following description which will be read in connection 25 with the accompanying drawing, wherein Figure 1 is a vertical section of a lock constructed in accordance with this invention, the view being taken on line 1—1 of Fig. 2. Fig. 2 is a horizontal section taken on line 2—2 of Fig. 1. Figs. 3 and 4 are vertical cross sections taken respectively on line 3—3 and 4—4 of Fig. 2, and Figs. 5 and 6 are elevational views of the key and assembled lock, respectively.

Throughout the views, the same reference numerals are applied to the same parts, and the sectional views are taken looking in the direction indicated by the arrows in the several views.

Referring to the drawing, the invention is illustrated, for the sake of simplicity, as embodied in a padlock of substantially the conventional form, as shown in Fig. 6, comprising the usual rectangular casing 10 and a J-shaped hasp or shackle bolt 11 movable vertically with respect to the casing to open position when the proper key 12 has been inserted and turned to withdraw the latch or latches which retain the hasp. The hasp 50 has its longer leg engaging in a bore 13 in the block 14 within the casing 10, and is limited in its vertical movement by a stop

pin 15 which operates in a recess 16 formed in the block. A coiled expansion spring 17 interposed between the lower end of the hasp and the bottom wall of the lock casing is adapted in the usual way to project the hasp upwardly so that the shorter leg leaves the opening 18. The hasp in the present instance is capable of being rotated, 60 so that the lock may be removed from the staple or the like to which it was applied.

The hasp 11 has a series of holes 19 drilled in its one side in which locking members or latches 20 in the form of plungers engage 65 under tension of the springs 21. It will be understood that in other forms of locks the hasp is not present and one or more latch members constitute the sole locking means. The latches 20 herein are shown operating 70 in a plurality of bores 22 provided in a block 23 disposed at one side of the hasp adjacent the block 14, as appears in Fig. 2. The latches 20 have recesses or grooves 24 formed in the sides thereof in which engage 75 the reduced offset ends of a plurality of operating bars 25. If desired, the bars 25 may be made an integral part of the latches 20. These bars are reciprocable in guideways 26 formed in the side of the block 14, as shown 80 in Fig. 2, and have their free ends offset variously, as illustrated, to overlie slightly the edges of a plurality of projections or lugs 27 formed about the sides of the opening 28 in a plate 29.

The plate 29 constitutes a ward member for the bit 30 of the key 12 which has recesses 31 formed in its edges corresponding to the projections 27 in the plate 29. Buttons 32 in the walls of the casing 10 act as 90 bearings for the stem 33 of the key 12 when the same has been inserted into the lock through the keyhole or slot 34. The bit 31 of the key is made to pass the ward member so that the bars 25 may be engaged and moved to release the latches 20 to open the lock in the usual way. It will be seen that when the projections 27 and recesses 31 are brought into register the ends of the bars 25 lap the joint thus formed so that upon 95 the further rotation of the key, the bit passes the plate, actuates the bars and thus opens the lock.

In Fig. 5 the plate 29 has been shown in

dotted lines as indicative of the manner in which the plate 29 and the key 12 may be formed from a single blank. In this way the possibility of non-conformity of the bit 5 of the key to the opening in the plate is reduced to a minimum.

It is apparent from the foregoing description that the invention provides a unique form of lock of this kind which is practically inviolable and which lends itself to manufacture according to the regular method of permutation in various forms as, for example, in one hundred and twenty variations where five projections and recesses 10 are used or seven hundred and twenty variations where six are used, and so on. Innumerable modifications are possible, however, by merely locating the recesses and projections unequal distances apart or by 15 locating the recesses upon either or opposite sides of the bit of the key, and the projections likewise on either or opposite sides of the opening 28 in the plate 29 as illustrated.

It will be apparent from the foregoing 20 that because the ward plate 29 is located as shown edgewise inside the casing to one side of the keyhole or slot the lock is practically invulnerable so far as opening it with a pick or the like is concerned. Furthermore, 25 it would be practically impossible to ascertain anything definite concerning the number or arrangement of projections in the opening because the plate is disposed edgewise to the keyhole and the latter extends 30 obliquely thereto.

The invention although illustrated as embodied in a padlock is also capable of adaptation to types of locks such, for example, as the flat cabinet type lock previously mentioned or other locks and also particularly 40 those which employ latch members only and wherein haeps and the like are not used.

The invention is capable of considerable modification without departure from the 45 spirit of the invention. It is therefore to be understood that it is intended to embody in the appended claims legitimate variations which would occur to one skilled in the art to which this invention relates.

50 I claim as my invention:

1. The combination in a lock having a casing, of a locking latch, a bar to operate the same, a key member insertable in said casing to actuate said bar, and a ward member for said key member, one of said members having recesses formed therein and the other having projections, said projections and recesses being complementary to permit the movement of said key member past 55 said ward member to actuate said latch operating bar.

2. The combination in a lock having a latch, a member for operating the same, a key for actuating said member, and means

between said key and operating member arranged to be passed by the key in its operating movement, said means including a projection on one of said relatively movable elements, a recess to receive said projection formed in the other of said elements, said 60 operating member being disposed so it laps the joint at the projection and recess when the proper key is used to open the lock whereby it may be actuated upon the relative movement of the elements to operate 75 said latch.

3. The combination in a lock having a latch member, a key to operate the same, said key being formed of sheet metal, and a member formed as of the same blank as 80 said key interposed between said key and latch member whereby said latch cannot be operated excepting by said key.

4. The combination in a lock having a latch member, of a key and a stationary 85 ward member for the key, said key and ward member having interfitting projections and notches arranged when substantially complementary to permit of the movement of the key relative to the ward member to 90 operate the latch member.

5. The combination in a lock having a casing, of a latch member, means adapted to be actuated to operate the same, a contoured key for actuating said means, and 95 a member having an opening therein the counterpart of the bit of said key whereby said member and key are interfittable to permit relative movement of the members in the opening of the lock. 100

6. The combination in a lock having a casing, of a latch member, a key for operating the same, said casing having a keyhole to receive said key, a ward member disposed in front of said latch member and 105 arranged to be passed by said key before the same operates said latch member, said ward member being disposed edgewise and to one side of said keyhole.

7. The combination in a lock comprising 110 a casing having a keyhole therein and a key adapted to be entered in said keyhole and rotated on a horizontal axis to operate the lock, a latch member, a bit on said key adapted to be revolved in a vertical plane 115 in the rotation of said key to operate said latch, and means in said casing individual to each lock arranged to intercept the operation of the bit unless the same is properly conformed to said means.

8. The combination in a lock comprising 120 a casing having a keyhole therein, of latch members in said casing operable rectilinearly at one side thereof, a plurality of operating members connected to the latch members and extending therefrom toward the keyhole in staggered relation, and a key 125 having a bit comprising portions adapted

individually to engage each of said members to open the lock.

9. The combination in a lock comprising a casing having a keyhole in the side wall thereof and a key adapted to be entered in said keyhole to operate the lock, said key having a bit extending laterally from the stem thereof, of a latch member disposed in said casing to one side of said keyhole, a block for supporting and guiding the same, said member comprising an operating portion projecting toward said keyhole, and a ward member disposed in said casing between the keyhole and said operating portion, said member having an opening therein to correspond to the contour of the bit of the key whereby only a special bit may pass through said opening to operate said latch member.

20 10. The combination in a lock comprising a casing provided with a keyhole opening through a side wall thereof and a key adapted to be entered in said keyhole to operate the lock, said key having a bit extending 25 transversely from the inner end of its stem, of a latch member disposed in said casing and supported to move horizontally toward and away from said keyhole, said member comprising an operating portion projecting 30 toward said keyhole and a member disposed in said casing in front of said operating portion provided with an opening contoured to the special bit of the key whereby only the special key may be entered into said lock 35 to operate the same.

11. The combination in a lock comprising a casing having a horizontal keyway therein and a key adapted to be entered in said keyway to operate the lock, of a latch member, a ward plate at one side of said keyway between it and said latch member, said key having a bit portion projecting transversely from the stem thereof adapted to be moved into and past the plane of said plate in 45 operating said latch member, said plate having an opening therein to receive said bit and permit the passage thereof therethrough, said bit and the edges of said opening being provided with projections and recesses individual to each lock whereby only the special key will have a bit capable of passing through said opening, said latch member having operating portions projecting slightly into the opening in said plate and lap- 50 ping the joint between the projections and recesses whereby said bit must correspond accurately to said opening to engage said portions to operate the latch.

12. The combination in a lock comprising 60 a casing having a keyway therein and a key adapted to be entered in said keyway to rotate on a horizontal axis, of a latch member, a ward member in front of said latch member, said key having a bit portion on the

inner end of its stem adapted to be moved 65 toward and past said ward member to operate said latch member, said ward member and the bit of said key having complementary conformations individual to each lock whereby only the special key will have a bit 70 capable of passing said ward member, said latch members having operating portions projecting into the path of said bit portion to be operated by the same after the same passes said ward member.

13. The combination in a lock comprising a casing having a keyhole therein, of latch members in said casing, a plurality of operating members connected to the latch members and extending therefrom toward the 80 keyhole, and a key having a bit comprising portions adapted individually to engage each of said members to open the lock.

14. In a lock, the combination of a casing having a pair of opposed walls, a locking member movable longitudinally between said walls and in a direction parallel thereto, a member fixed with reference to said casing, a member having one end operatively connected with said locking member and its 90 other end abutting the inner side of said fixed member, and a key adapted to engage said operating member as it clears said fixed member.

15. In a lock, the combination of a locking 95 member, a spring normally holding said member in its locking position, and means for actuating said member against the tension of its spring including an operating member, a fixed member disposed in a position substantially perpendicular to the path of movement of said operating member and adapted to permit of such movements with respect thereto, and a key having a notch therein adapted to clear said fixed 100 member and to engage said operative member.

16. In a lock, the combination of a locking element, a spring normally holding said element in its locking position, an operating member operatively associated with said element to move it, a fixed member abutting one side of said operating member at the free end of the latter, and a key having a notch therein adapted snugly to receive said 110 fixed member while the key engages with the free end of the operating member at the base of its notch.

17. In a lock, the combination of locking 115 means, a plurality of operating members for said locking means, a member having a plurality of projections each adapted to engage with one side of an operating member near one end of the latter, and a key having a plurality of notches therein adapted to receive snugly the respective projections while the key engages the ends of said operating members at the bases of its notches.

18. In a lock, the combination of a casting, a member fixed transversely of the casting and having a plurality of projections, locking means normally spring pressed into holding position, and operating means including a plurality of members operatively associated with said locking means and abutting the free ends of said projections, and a key adapted to engage said free ends of the operating members and having a plurality of notches therein adapted snugly to receive said projections.

In testimony whereof, I have hereunto set my hand.

WILLIAM C. GRAVES.
